UNITED STATES PATENT OFFICE.

EDWARD J. ZAHNER, OF KANSAS CITY, MISSOURI.

SHEET-METAL DOOR.

1,091,905.

Specification of Letters Patent. Patented Mar. 31, 1914.

Application filed May 24, 1912. Serial No. 699,554.

To all whom it may concern:

Be it known that I, EDWARD J. ZAHNER, a citizen of the United States, and a resident of Kansas City, in the county of Jackson and State of Missouri, have invented certain new and useful Improvements in Sheet-Metal Doors, of which the following is a specification.

My invention relates to improvements in doors.

The object of my invention is to provide a door which is sanitary, is easily manufactured, and rigid in construction.

My invention is particularly adapted for use in built up metallic doors of the flush panel type.

In the accompanying drawings, which illustrate the preferred form of my invention, Figure 1 is a side view of my improved door, parts being broken away. Fig. 2 is a view on the line *a—b* of Fig. 1. Fig. 3 is an enlarged sectional view, partly broken away, on the line *c—d* of Fig. 1. Fig. 4 is a top edge view of the door. Fig. 5 is a cross section enlarged and partly broken away, on the line *e—f* of Fig. 1.

Similar reference characters designate similar parts in the different views.

The door has a hollow body comprising two right angled members which I term panel members, each of which forms one panel 1 and one side edge 2 of the body. Each portion 2 at one longitudinal edge has an inwardly extending flange 3 which is fitted in a longitudinal groove 4 provided in the other panel member. Preferably said grooves 4 are formed by securing by spot welding or otherwise to the inner sides of the panel portions 1 of the panel members 5 respectively longitudinal metal strips 5 having each an inwardly offset portion 6 disposed at the inner side and overlapping the flange 3 of the opposite member.

To increase the strength and rigidity of the door I provide spacing means connecting the panel portions 1. Preferably this spacing means comprises one or more spacing members 7 secured to the inner side of one panel member and interlocked respectively with a corresponding number of spacing members 8 respectively secured to the inner side of the other panel member. Preferably the spacing members 7 and 8 are disposed longitudinally of the door, as shown in the drawings. The spacing members 7 and 8 are, preferably each of chan-

nel form and have their outer flanges 9 respectively secured by spot welding or otherwise to the inner sides of the panel members. The inner flanges 10 and 11 of the members 7 and 8 are disposed parallel with each other and abut against each other so as to prevent the panel members moving toward each other. The flange 10 has an inwardly turned flange 12 located in a longitudinal groove formed by having the flange 11 provided with a U-shaped extension 13, the groove facing the flange 10 of the member 8. This construction is best illustrated in Fig. 5.

Preferably the panel members have secured respectively to the inner sides of the side edge portions 2, flat bars 14 which serve to increase the strength and rigidity of the door. Channel end members 15 and 16 are secured by spot welding or other suitable means to and between the panel members at the upper and lower ends respectively. The upwardly extending flanges of the channel end member 15 have their upper edges disposed slightly below the upper edges of the panel members and have mounted upon them a horizontal flat plate 17, which is secured by screws 18 to the horizontal portion of the member 15, the upper portion of the plate 17 being preferably flush with the upper edges of the panel members.

In making the improved door, the strips 5, bars 14 and interlocking members 7 and 8 are attached to their respective panel members before said members have been interlocked with each other. The panel members are then interlocked with each other and the members 7 with the members 8 by forcing the panel members endwise relative to each other, the flanges 3 being slipped lengthwise into the grooves 4, and the flanges 12 simultaneously drawn lengthwise into the grooves of the U-shaped extensions 13 of the flanges 11. It will be noted that the interlocking spacing members 7 and 8 hold the panel members from lateral movement in any direction. When the panel members have been slid to their proper positions, the end members 15 and 16 are mounted in their proper positions, after which the contacting portions of the panel members may be gas or spot welded to each other in the usual well known manner. The end members 15 and 16 may now, also, be gas or spot welded to the panel members, after

which the top plate 17 may be secured in position.

My invention provides a door which is light, fireproof, strong, durable, rigid, and which presents perfectly smooth outer surfaces, thereby providing a sanitary door which will not collect dirt or moisture and which may be easily cleaned.

I do not limit my invention to the structure shown and described, as modifications, within the scope of the appended claims, may be made without departing from the spirit of my invention.

Having thus described my invention, what I claim and desire to secure by Letters Patent, is:—

1. A door comprising a hollow body, and partition spacing means including two members secured respectively to opposite inner sides of the body intermediate of the side edges of the body and abutting against each other to prevent movement toward each other, each member having a channel facing toward the side of the body to which said member is secured, one flange of each channel being disposed in the channel of the other member.

2. A door comprising a hollow body, and two partition spacing members secured respectively to opposite inner sides of the body intermediate of the side edges of the body, each member having a laterally extending portion which abuts against the laterally ex-

tending portion of the other member, one of said laterally extending portions terminating in a channel which faces toward the side of the body to which the member having said portion is attached, the other laterally extending portion terminating in a flange located in said channel.

3. A door comprising a hollow body, and two channel partition spacing members having their outer flanges secured respectively to opposite inner sides of the body intermediate of the side edges of the body, and having their inner flanges provided with interlocking means for holding the members from lateral movement relative to each other.

4. A door comprising a hollow body, and two channel partition spacing members having their outer flanges secured respectively to opposite inner sides of the body intermediate of the side edges of the body and their inner flanges disposed side by side, one inner flange having a U shaped return bend and the other inner flange having a laterally turned portion disposed between the arms of said U shaped return bend of the other inner flange.

In testimony whereof, I have signed my name to this specification in presence of two subscribing witnesses.

EDWARD J. ZAHNER.
